H. H. WALLACE,
ELECTROTHERMAL ROBE.
APPLICATION FILED JAN. 23, 1918.

1,278,530.

Patented Sept. 10, 1918.

UNITED STATES PATENT OFFICE.

HOWARD H. WALLACE, OF SALT LAKE CITY, UTAH.

ELECTROTHERMAL ROBE.

1,278,530.

Specification of Letters Patent. Patented Sept. 10, 1918.

Application filed January 23, 1918. Serial No. 213,425.

To all whom it may concern:

Be it known that I, HOWARD H. WALLACE, a citizen of the United States, residing at Salt Lake City, in the county of Salt Lake 5 and State of Utah, have invented certain new and useful Improvements in Electro-thermal Robes, of which the following is a specification.

My invention relates to electro-thermal garments, and has for its object to provide a blanket robe which may be wrapped and fastened about a person to treat such person medically with electrically generated heat and consists of an outer slip or covering within which is carried an inner part or portion which has resistance wires sewed thereon with the terminals so positioned that when the completed robe is folded about the person and secured that the fastening means will form efficient electric contacts and close electric circuits whereby the different parts of the body may be given electro-thermal treatment.

These objects I accomplish with the apparatus illustrated in the accompanying drawings in which similar letters and numerals of reference indicate like parts throughout the several figures and as described in the specification forming a part of this application and pointed out in the appended claims.

In the drawings in which I have shown a substantial embodiment of my invention, Figure 1 is a plan view of the wire carrying portion. Fig. 2 is a plan view of the outer slip or covering, parts cut away. Fig. 3 is a view of the apparatus when folded and fastened on the legs of a figure shown therein and before the sides are folded into treatment position. Fig. 4 is a plan of one of the insulating members before it is sewed on the wire carrying portion and over the contacts. Fig. 5 shows plan and section views of the contact members.

In giving electro-thermal treatments the heat causes the patient to perspire freely and the portion of the robe in contact with the body is dampened and often filled with perspiration thrown off by the body, so that it is highly desirable to change the slip or outer covering of the robe for each treatment. In order that the heat may be applied to the particular parts of the body requiring treatment the robe must be so constructed that electric circuits may be made easily and quickly and to carry out

the above the present invention consists of a slip or outer covering A made of material that may be laundered and conforming to the general form of the robe. For convenience in removing the heat element or wire carrying portion snap fastenings 1, similar to those used at the wrists of gloves, are provided in the adjacent edges of said slip A, by means of which said slip may be closed or opened as desired. A heat element B is provided for use within said slip A, and is to be inserted at the end of said slip and fastened therein by means of said clasps 1. The said heat element consists of a piece of cloth or other flexible fiber 2 made to conform to the shape of the said slip A, and on which is sewed resistance wires a, b, and c. The said wire a is fastened to said cloth 2 by overcast stitching 3 crossing in zigzag courses over said wire, which wire is laid in parallel courses, and commencing at the upper left hand corner it is stitched parallel with the edge of said cloth 2 to the lower left hand corner, then turned and led up and down over said cloth 2 and attached to one member 4 of the clasp at a point marked 6 in the drawings. A wire b has one end electrically attached to the other member 5 of the clasp which is secured at the lower left hand corner of the leg cover portion 2' of said heat element B at the place marked 8 in the drawings, and said wire is fastened on said cloth by similar overcast stitching 3 parallel with the edge of said cloth and led up and down over said main portion 2 in parallel courses and ending at the lower right hand corner of said portion 2' at a place marked 9 in the drawing, where it is electrically attached to another member 5 of a similar clasp to that previously described. A resistance wire c similar to said wires a and b is likewise attached to the member 4 of the clasp which is fastened in the said cloth 2 at practically the center of the right half portion of said cloth, shown at 7, and stitched to said cloth by overcast stitching over said wire in parallel leads up and down over said main portion 2 of said cloth to the upper right hand corner, and then across the upper end of said cloth 2 to the upper left hand corner. The wires a and c are connected with a source of electric energy, not shown. Each of the members 4 and 5 of said clasps are covered by a piece of asbestos flexible fiber cloth 16 as shown in Fig. 4 and said piece

stitched securely on said cloths 2 and 2' where the clasps are required thus providing an insulating heat resisting covering for said clasps to prevent burning of the robe 5 by the electricity used to charge the wires *a*, *b* and *c*. A row of said clasp members 4 and 5 is provided on a longitudinal middle line *x x* of said slip A but without electrical connections. With the robe assembled by 10 placing the wire carrying member B within the slip A, the robe may be fastened on the patient or person to be treated by folding the portion 2' of the heat element and its covering of the part of the slip over the 15 legs of the person and pressing the members 4 and 5 of the clasps into engagement at points 6 and 7 and folding the side portions of the main part 2 of the heat element B and the similar portions of the said slip A, over 20 the breast of the person being treated. The engaging of the clasp members 4 and 5 at the respective points 6 and 8, and 7 and 9 closes an electric circuit and electricity passing over the resistance wires *a*, *b* and *c* will 25 generate heat around the legs of the person which will be retained around the body by the folds of the robe. Induced electric currents will be developed around the said wires *a*, *b* and *c* which with the heat so generated as above will be applied to the person 30 being treated. The essential features of my invention are the covering of the heat element by the detachable slip, the form of the robe and the contact members 4 and 5 of 35 the clasps.

Having thus described my invention I desire to secure by Letters Patent and claim:—

1. An electro-thermal robe consisting of a 40 detachable slip, having a central portion extended at one end as a leg covering; a wire

carrying flexible robe conforming in general shape to said slip and to be used within said slip; resistance wires stitched in parallel leads on said last described robe terminating at one corner thereof and connected 45 into a circuit by folding and fastening said robe in place; and clasp members to which the terminals of said wires are attached which close an electric circuit when engaged one with the other. 50

2. An electro-thermal robe consisting of a detachable slip; a wire carrying flexible robe conforming to the shape of said slip and used therein; resistance wires stitched in parallel rows on one face of said last described robe with the ends so terminating that they may be brought into electric circuit when the robe is folded and fastened in place; and snap members attached to the ends of said wires which when pressed into 60 engagement one with the other will form one electric circuit. 65

3. An electro-thermal robe consisting of a detachable slip; a wire carrying flexible robe conforming to the shape of said slip and used therein; resistance wires stitched in parallel rows on one face of said last described robe with the ends so terminating that they may be brought into an electric circuit when the robe is folded and fastened 70 in place; snap members attached to the ends of said wires which when pressed into engagement one with the other will form one continuous circuit; and a piece of asbestos fiber insulation stitched on opposite 75 faces of said snap members and to said robe.

In testimony whereof I have affixed my signature.

HOWARD H. WALLACE.
